UNITED STATES PATENT OFFICE

90,737

DESIGN FOR AN AUTOMOBILE RADIATOR EMBLEM

Louis J. Taber, Columbus, Ohio, assignor to The
National Grange of the Patrons of Husbandry
of Washington, D. C.

Application June 17, 1933. Serial No. 48,433

Term of patent 7 years

To all whom it may concern:

Be it known that I, Louis J. TABER, a citizen of the United States, residing at Columbus, in the county of Franklin and State of Ohio, have invented a new, original, and ornamental Design for an Automobile Radiator Emblem, of which the following is a specification, reference being had to the accompanying drawing, forming part thereof.

Figure 1 is a front elevation of an automobile radiator emblem showing my new design; and Figure 2 is a side elevation of the same.

I claim:

The ornamental design for an automobile radiator emblem as shown.

LOUIS J. TABER.
